CARBURETOR

Filed June 25, 1945

FIG. 1.

UNITED STATES PATENT OFFICE

2,404,645

CARBURETOR

Marion Mallory, Detroit, Mich.

Application June 25, 1945, Serial No. 601,455

14 Claims. (Cl. 123—123)

1

This invention relates to a carburetor for an internal combustion engine.

Where a governor throttle valve is positioned between the manual throttle valve and the engine, then when the engine is working under no load or real light loads and the governor valve is almost closed and the manual throttle valve is wide open, the fuel mixture becomes very lean thereby causing overheating and rolling of the engine which in turn causes the governor valve to surge.

It is the object of this invention to overcome the above objection which results from the use of an automatically operated governor valve between the carburetor and the engine. This object is accomplished simply and efficiently by utilizing the intake passageway pressures adjacent the governor throttle valve to control a power jet which opens and admits more fuel through the main jet whenever the above conditions obtain.

Fig. 1 is a vertical section through my carburetor.

Fig. 2 is a fragmentary vertical section showing a modified form of the same.

The parts forming my carburetor are as follows: carburetor housing 1, governor body 2 positioned between the carburetor housing and the engine, intake passageway 3, air inlet 4, outlet to the engine 5, manually controlled throttle valve 6 preferably of the butterfly type, valve shaft 7, crank arm 8 fixed on shaft 7, rod 9 for controlling carburetor throttle valve 6, governor throttle valve 10 preferably of the butterfly type mounted on shaft 11, float bowl 12, fuel level 13, venturi 14, main jet 15 connected by passageway 16 with orifice 17 in fuel bowl 12, idle jets 18 and 19 connected by passageway 20 with passageway 16, power jet 21 communicating with passageway 16 (the orifices 17 and 21 are positioned below fuel level 13), needle valve 22 controlling power jet 21, piston 23 in cylinder 24, arm 25 connecting piston 23 and valve 22, compression spring 26 tending to raise piston 23 and hold valve 22 open, passageway 27 connecting cylinder 24 with orifice 28 positioned on the atmosphere side of valve 10 when nearly closed.

It is understood that governor valve 10 is automatically operated and may be any of the known automatically operated types of governor such as the unbalanced velocity type governor valve, the engine driven centrifugal weight actuated type of governor, or the intake passageway pressure actuated governor such as shown in my copending application Serial No. 466,961, filed November 25, 1942.

2

The operation of my carburetor is as follows: As shown in the drawing throttle valve 6 is wide open and governor valve 10 is almost closed. Under these conditions the pressure at orifices 18 and 19, which are the customary idle jets of the carburetor, will be substantially atmospheric and the only fuel obtained by the engine is that drawn out of main jet 15 through venturi 14. With governor valve 10 nearly closed, the velocity through venturi 14 is so low that in the absence of power jet 21 so little mixture would be drawn out of main jet 15 that the mixture would become too lean. However, under the above conditions, orifice 28 is on the atmosphere side of governor valve 10 and in substantially atmospheric pressure, which pressure establishes itself in cylinder 24 below piston 23 and permits spring 26 to raise piston 23 and lift needle valve 22 from power jet 21 and thereby admit more fuel through main jet 15 to the engine. As soon as valve 10 opens wide enough to permit more air to flow through venturi 14, then orifice 28 will be positioned between governor valve 10 and the engine, that is, in the intake passageway vacuum. Under such conditions the intake passageway vacuum on the engine side of valve 10 will now establish itself in cylinder 24 thereby drawing piston 23 down against compression spring 26 and thereby closing power jet 21. However, closing of power jet 21 under such conditions will not cause the mixture at main jet 15 to become too lean because even though power jet 21 is closed the velocity through venturi 14 by jet 15 will be high due to the opening of governor valve 10 and sufficient fuel will be drawn out of main jet 15 to satisfy the fuel mixture requirements of the engine.

The modified form of my carburetor shown in Fig. 2 is identical with that shown in Fig. 1 except that passageway 27 terminates at orifice 31 which is positioned at all times between the engine and governor valve 10. In addition, I provide orifice 31 which is positioned between governor valve 10 and valve 6, cylinder 32, compression spring 33, orifice 34 connecting cylinder 32 with the intake passageway below piston 35, piston 35, orifice 36 between passageway 27 and cylinder 32 above piston 35. Orifice 31 can be positioned so that it is on the atmosphere side of valve 10 in all positions of valve 10, but preferably orifice 31 is located adjacent valve 10 so that orifice 31 is on the atmosphere side of valve 10 when valve 10 is closed sufficiently to cause the velocity to drop so low in venturi 14 that the fuel mixture becomes too lean and in wider open po-

sitions of valve 10, orifice 31 will pass onto the engine side of valve 10.

The operation of the modified form is as follows: When throttle 10 becomes nearly closed or far enough closed to cause the velocity to drop so low in venturi 14 that the mixtures become too lean, the high vacuum between governor valve 10 and the engine will establish itself through orifice 34 in cylinder 32 beneath piston 35 thereby drawing piston 35 downwardly and placing orifice 31 in communication with orifice 36 and passageway 27. Since the pressure at orifice 31 at this time will be substantially atmospheric, this pressure will establish itself in cylinder 24 beneath piston 23 and spring 26 will move piston 23 upwardly thereby opening needle valve 22 and permitting fuel to be drawn through power jet 21 into passageway 16 thereby enrichening the fuel mixture. When governor valve 10 opens far enough so that the velocity through venturi 14 by jet 15 will be high enough to draw sufficient fuel from orifice 17 and jet 15 to satisfy the fuel mixture requirements of the engine, then piston 35 will rise and shut off communication between orifices 31 and 36 but at this time the intake passageway vacuum at orifice 30 will be established through passageway 21 in cylinder 24 thereby causing piston 23 to move downwardly and close valve 22. Here again the mixture at main jet 15 will not become too lean because the opening of governor valve 10 will increase the velocity through venturi 14 and draw more fuel from main jet 15. Where the engine is operating under high load with both governor valve 10 and throttle valve 6 wide open, then, particularly at lower engine speeds, the power jet 21 will be open and in operation thus enriching the fuel mixture for such high load operation.

I claim:

1. In a carburetor for an internal combustion engine having an intake passageway, a main fuel jet in said passageway, a source of fuel connected to said main jet, a governor valve in said passageway on the engine side of said main jet, an additional fuel supply system for supplying fuel into said intake passageway including an auxiliary jet, and means actuated by changes of pressure in the intake passageway for controlling said auxiliary jet, said means responding to substantially atmospheric pressure in the intake passageway on the atmosphere side of the governor valve when nearly closed to open said auxiliary jet and admit fuel into the intake passageway.

2. In a carburetor for an internal combustion engine having an intake passageway, a power jet for supplying fuel into said passageway, a source of fuel connected to said power jet, a governor valve on the engine side of said power jet, means actuated by changes of pressure in the intake passageway for controlling said power jet, said means responding to the pressure in the intake passageway on the atmosphere side of said governor valve when nearly closed to open said power jet and admit fuel into said intake passageway, and said means responding to the pressure in the intake passageway on the engine side of said governor valve when opened to shut off said power jet.

3. In a carburetor for an internal combustion engine having an intake passageway, a main fuel jet in said passageway, a source of fuel connected to said jet, a governor valve on the engine side of said main jet, a power jet for feeding fuel into said intake passageway, means actuated by changes of pressure in the intake passageway ad-

jacent said governor valve for controlling said power jet, a conduit connecting said pressure actuated means with the intake passageway on the atmosphere side of and adjacent the governor valve when nearly closed and with the intake passageway on the engine side of said governor valve when the governor throttle valve is opened beyond idle position to an extent where the fluid velocity by the main jet will draw fuel from the main jet at a rate to produce a sufficiently rich mixture whereby said pressure actuated means responds to the pressure in the intake passageway on the engine side of said governor valve and closes said power jet.

4. In a carburetor for an internal combustion engine having an intake passageway, a venturi in said intake passageway, a main fuel jet in said venturi, a source of fuel connected to said jet, a governor valve on the engine side of said main jet, a power jet for feeding fuel into said intake passageway, means actuated by changes of pressure in the intake passageway adjacent said governor valve for controlling said power jet, a conduit connecting said pressure actuated means with the intake passageway on the atmosphere side of and adjacent the governor valve when nearly closed whereby said pressure actuated means responds to the pressure in the intake passageway on the atmosphere side of the governor valve and opens said power jet, said conduit connecting said pressure actuated means with the intake passageway on the engine side of said governor valve when the governor throttle valve is opened beyond idle position to an extent where the fluid velocity by the main jet will draw fuel from the main jet at a rate to produce a sufficiently rich mixture whereby said pressure actuated means responds to the pressure in the intake passageway on the engine side of said governor valve and closes said power jet.

5. In a carburetor for an internal combustion engine having an intake passageway, a venturi in said intake passageway, a main fuel jet in said venturi, a source of fuel connected to said jet, a governor valve on the engine side of said main jet, a manual throttle valve between the governor valve and the main jet, a power jet for feeding fuel into said intake passageway, means actuated by changes of pressure in the intake passageway adjacent said governor valve for controlling said power jet, a conduit connecting said pressure actuated means with the intake passageway on the atmosphere side of and adjacent the governor valve when nearly closed whereby when the manual throttle valve is wide open said pressure actuated means responds to the pressure in the intake passageway on the atmosphere side of the governor valve and opens said power jet, said conduit connecting said pressure actuated means with the intake passageway on the engine side of said governor valve when the governor throttle valve is opened beyond idle position to an extent where the fluid velocity by the main jet will draw fuel from the main jet at a rate to produce a sufficiently rich mixture whereby when the manual throttle valve is wide open said pressure actuated means responds to the pressure in the intake passageway on the engine side of said governor valve and closes said power jet.

6. In a carburetor for an internal combustion engine having an intake passageway, a venturi in said intake passageway, a main fuel jet in said venturi, a source of fuel connected to said jet, a governor valve on the engine side of said main jet, a manual throttle valve between the gov-

ernor valve and the main jet, an idle jet between the manual throttle valve and the governor valve for feeding fuel into said intake passageway when the manual throttle valve is closed for idling the engine, a power jet for feeding fuel into said intake passageway, means actuated by changes of pressure in the intake passageway adjacent said governor valve for controlling said power jet, a conduit connecting said pressure actuated means with the intake passageway on the atmosphere side of and adjacent the governor valve when nearly closed whereby when the manual throttle valve is wide open said pressure actuated means responds to the pressure in the intake passageway on the atmosphere side of the governor valve and opens said power jet, said conduit connecting said pressure actuated means with the intake passageway on the engine side of said governor valve when the governor throttle valve is opened beyond idle position to an extent where the fluid velocity by the main jet will draw fuel from the main jet at a rate to produce a sufficiently rich mixture whereby when the manual throttle valve is wide open said pressure actuated means responds to the pressure in the intake passageway on the engine side of said governor valve and closes said power jet.

7. In a carburetor for an internal combustion engine having an intake passageway, a main fuel jet in said passageway, a source of fuel connected to said jet, a governor valve on the engine side of said main jet, a power jet on the atmosphere side of said governor valve for feeding fuel into said intake passageway, a valve controlling said power jet, means actuated by changes of pressure in the intake passageway adjacent said governor valve for controlling said power jet valve, a conduit connecting said pressure actuated means with the intake passageway on the atmosphere side of and adjacent the governor valve when nearly closed whereby said pressure actuated means responds to the pressure in the intake passageway on the atmosphere side of said governor valve and opens said power jet valve, said conduit connecting said pressure actuated means with the intake passageway on the engine side of said governor valve when the governor throttle valve is opened beyond idle position to an extent where the fluid velocity by the main jet will draw fuel from the main jet at a rate to produce a sufficiently rich mixture whereby said pressure actuated means responds to the pressure in the intake passageway on the engine side of said governor valve and closes said power jet valve.

8. In a carburetor for an internal combustion engine having an intake passageway, a venturi in said intake passageway, a main fuel jet in said venturi, a source of fuel connected to said jet, a governor valve on the engine side of said main jet, a power jet on the atmosphere side of said governor valve for feeding fuel into said intake passageway, a valve controlling said power jet, means actuated by changes of pressure in the intake passageway adjacent said governor valve for controlling said power jet valve, a conduit connecting said pressure actuated means with the intake passageway on the atmosphere side of and adjacent the governor valve when nearly closed whereby said pressure actuated means responds to the pressure in the intake passageway on the atmosphere side of the governor valve and opens said power jet, said conduit connecting said pressure actuated means with the intake

5 valve when the governor throttle valve is opened beyond idle position to an extent where the fluid velocity by the main jet will draw fuel from the main jet at a rate to produce a sufficiently rich mixture whereby said pressure actuated means responds to the pressure in the intake passageway on the engine side of said governor valve and closes said power jet valve.

9. In a carburetor for an internal combustion engine having an intake passageway, a main fuel jet in said passageway, a source of fuel connected to said jet, a governor valve on the engine side of said main jet, a power jet for feeding fuel into said intake passageway, means actuated by changes of pressure in the intake passageway adjacent said governor valve for controlling said power jet, an orifice positioned in the intake passageway on the atmosphere side of and adjacent the governor valve when nearly closed to a position so that the fuel drawn from the main jet by the air flowing past said jet provides a too lean mixture, a conduit connecting said pressure actuated means with said orifice whereby the governor valve in closing reaches said above specified position the pressure actuated means responds to the pressure in the intake passageway on the atmosphere side of the governor valve and opens said power jet, said orifice passing on to the engine side of the governor valve when the governor valve is opened to a position where the air flow by said main jet will draw sufficient fuel through the jet to produce a proper fuel mixture whereby said pressure actuated means responds to intake passageway pressure and closes said power jet.

10. In a carburetor for an internal combustion engine having an intake passageway, a main fuel jet in said passageway, a source of fuel connected to said jet, a governor valve on the engine side of said main jet, a power jet for feeding fuel into said intake passageway, means actuated by changes of pressure in the intake passageway adjacent said governor valve for controlling said power jet, an orifice positioned on the atmosphere side of and adjacent the governor valve when closed to a position where the air flow by the main jet will draw fuel from the main jet at a rate to produce a too lean mixture, a second orifice positioned at all times on the engine side of the governor valve, a conduit connecting said first and second orifices with said pressure actuated means, a valve actuated by changes of pressure in the intake passageway on the engine side of said governor valve for controlling said first mentioned orifice, said pressure actuated valve closing said first mentioned orifice whenever the governor valve is opened sufficiently to bring said first mentioned orifice on to the engine side of said governor valve, said pressure actuated valve opening said first mentioned orifice when the governor valve is closed sufficiently to bring said first mentioned orifice on to the atmosphere side of said governor valve whereby said pressure actuated means responds to the pressure in the intake passageway on the atmosphere side of said governor valve and opens said power jet.

11. In a carburetor for an internal combustion engine having an intake passageway, a throttle valve, a main fuel jet in said passageway on the atmosphere side of said throttle valve, a source of fuel connected to said jet, a governor valve on the engine side of said main jet, a power jet for feeding fuel into said intake passageway, means actuated by changes of pressure in the intake passageway for controlling said power jet, an

orifice positioned in said intake passageway between the governor and throttle valves, a second orifice positioned at all times on the engine side of the governor valve, a conduit connecting said first and second orifices with said pressure actuated means, a valve actuated by changes of pressure in the intake passageway on the engine side of said governor valve for controlling said first mentioned orifice, said pressure actuated valve closing said first mentioned orifice whenever the throttle valve is substantially wide open and the governor valve is opened sufficiently to cause the fluid velocity by said main fuel jet to draw sufficient fuel from said main jet to produce a sufficiently rich mixture, said pressure actuated valve opening said first mentioned orifice when the throttle valve is substantially wide open and the governor valve is closed sufficiently to cause the velocity to drop so low by the main jet that the fuel mixture becomes too lean whereby said pressure actuated means responds to the pressure in the intake passageway on the atmosphere side of said governor valve and opens said power jet.

12. In a carburetor for an internal combustion engine having an intake passageway, a throttle valve in said intake passageway, a main fuel jet in said passageway on the atmosphere side of said throttle valve, a source of fuel connected to said main jet, a governor valve in said passageway on the engine side of said throttle valve, an additional fuel supply system for supplying fuel into said intake passageway including an auxiliary jet, and means actuated by changes of pressure in the intake passageway on the engine side of said throttle valve for controlling said auxiliary jet, said means responding to substantially atmospheric pressure in the intake passageway on the atmosphere side of the governor valve when nearly closed and when said throttle valve is substantially wide open to open said auxiliary jet and admit fuel into the intake passageway.

13. In a carburetor for an internal combustion engine having an intake passageway, a throttle

valve in said intake passageway, a main fuel jet in said passageway on the atmosphere side of said throttle valve, a source of fuel connected to said main jet, a governor valve in said passageway on the engine side of said throttle valve, an additional fuel supply system including an auxiliary jet for supplying fuel into said intake passageway on the atmosphere side of said throttle valve, and means actuated by changes of pressure in the intake passageway on the engine side of said throttle valve for controlling said auxiliary jet, said means responding to substantially atmospheric pressure in the intake passageway on the atmosphere side of the governor valve when nearly closed and when said throttle valve is substantially wide open to open said auxiliary jet and admit fuel into the intake passageway, said means also responding to substantially atmospheric pressure in the intake passageway such as occurs when both the governor and throttle valves are substantially wide open and the engine is operating under high load.

14. In a carburetor for an internal combustion engine having an intake passageway, a main fuel jet in said passageway, a source of fuel connected to said main jet, a governor valve in said passageway on the engine side of said main jet, an additional fuel supply system including an auxiliary jet for supplying fuel into said intake passageway on the atmosphere side of said governor valve, and means actuated by changes of pressure in the intake passageway for controlling said auxiliary jet, said means responding to substantially atmospheric pressure in the intake passageway on the atmospheric side of the governor valve when nearly closed to open said auxiliary jet and admit fuel into the intake passageway, said means also responding to substantially atmospheric pressure in the intake passageway such as occurs when the governor valve is in wide open position and the engine is operating under high load to thereby open said auxiliary jet and admit fuel into the intake passageway.

MARION MALLORY.
